UNITED STATES PATENT OFFICE.

LAWRENCE M. PROCTOR AND WILLIAM H. PROCTOR, OF OGDENSBURG, N. Y.

TOBOGGAN.

SPECIFICATION forming part of Letters Patent No. 340,731, dated April 27, 1886.

Application filed March 19, 1886. Serial No. 195,818. (No model.)

To all whom it may concern:

Be it known that we, LAWRENCE M. PROCTOR and WILLIAM H. PROCTOR, citizens of the United States, residing at Ogdensburg, in the county of St. Lawrence and State of New York, have invented certain new and useful Improvements in Toboggans, of which the following is a specification, reference being had to the accompanying drawings.

10 The object of our invention is to provide toboggans which will combine suitable lightness and convenience, the greatest possible strength and durability, and which will present on their under sides frictional surfaces of lesser extent 15 than the toboggans heretofore generally in use, our invention being in part an improvement on the toboggan shown and described in the application of William H. Proctor and S. H. Miller, Serial No. 191,961, filed February 15, 1886.

In the accompanying drawings, Figure 1 is a plan view of a toboggan embodying our invention. Fig. 2 is a side view, partly in section, of the same. Fig. 3 is a cross-section on 25 the line 3 3, Fig. 1; and Fig. 4 is a cross-section showing a slightly modified form of our invention.

The body of our toboggan is composed of flat thick and thin strips A, secured together 30 by cross-bars B, through which latter pass screws b into the strips A, as in the application of Proctor and Miller, above referred to, the weight of the toboggan and its load being sustained by the thick strips only, as in the 35 toboggan described by the said application.

To prevent the thin strips from pulling off from the screws b, should too much weight come on said strips, all of the strips are beveled at their edges, as clearly shown in Fig. 4c 3, the thick strips being undercut, so that the dovetailed or flaring-lips a at the edges of the thin strips will be received into the undercut or beveled recess at the edges of the thick strips. As all of the strips are closely fitted 45 together, it is obvious that by beveling the edges of the strips in the manner shown the thin strips will be supported at their edges throughout their entire lengths by the thick strips, so that liability of starting them from 50 the attaching-screws b will thus be avoided.

Instead of beveling the edges of the strips,

as shown in Fig. 3, the thin strips may be supported by small rectangular lips a' on their edges, fitting in corresponding undercut grooves at the edges of the thick strips, as 55 shown in Fig. 4; but this construction, although serving a very good purpose, we do not consider so good as that shown in Fig. 3, for the reason that the beveled lips at the edges of the strips are stronger than the rectangular lips, as will be obvious; but whether the strips are beveled, as shown in Fig. 3, or provided with rectangular lips and grooves, as in Fig. 4, it will be apparent that the thinner strips will have projecting lips at their 60 edges fitting in undercut grooves in the thicker strips.

C denotes the side rails of the toboggan these side rails being preferably secured in place by means of flexible fastenings c, consisting of thongs of gut or rawhide; or they may be of wire or other strong but flexible material. These flexible fastenings may extend through the strips A, or may be passed only beneath the cross-bars B, both of these arrangements of the fastenings being shown in Fig. 2, and the latter arrangement being considered preferable, for the reason that it will not mar the smoothness of the under side of the strips A. To raise the side rails, C, a sufficient distance above the strips A to permit the former to be grasped readily in carrying the toboggan, or in holding onto the same in riding without making the cross-bars B unnecessarily thick and heavy, we place small blocks 75 beneath the said side rails and above the cross-bars, said blocks being preferably grooved, as shown, for the reception of the side rails.

Having thus described our invention, we claim and desire to secure by Letters Patent— 9c

1. A toboggan the body of which is composed of flat strips of varying thickness, the thin strips having at their edges projecting lips, and the thick strips having undercut grooves, in which the said lips fit, substantially as set forth. 95

2. A toboggan the body of which is composed of alternate thick and thin strips having beveled edges, combined with cross-bars secured to said strips, substantially as set forth. 100

3. The combination, with the body and the

cross-bars of a toboggan, of the side rails and the blocks placed between said rails and cross-bars, whereby said rails are held a suitable distance above said body without making said cross-bars unnecessarily thick and heavy, substantially as set forth.

5 4. The combination, with the body of a toboggan, of the side rails, the cross-bars, the blocks between the latter and the side rails,

and the flexible fastenings for securing said rails in place, substantially as set forth.

In testimony whereof we affix our signatures in presence of two witnesses.

LAWRENCE M. PROCTOR.
WILLIAM H. PROCTOR.
